UNITED STATES PATENT OFFICE.

JOHN F. O'CONNOR, OF CHICAGO, ILLINOIS, ASSIGNOR TO WILLIAM H. MINER, OF CHICAGO, ILLINOIS.

ROLLER SIDE BEARING FOR RAILWAY-CARS.

1,096,939.

Specification of Letters Patent.

Patented May 19, 1914.

Application filed June 23, 1911. Serial No. 635,035.

To all whom it may concern:

Be it known that I, JOHN F. O'CONNOR, a citizen of the United States, residing in Chicago, in the county of Cook and State of Illinois, have invented a new and useful Improvement in Roller Side Bearings for Railway-Cars, of which the following is a specification.

This invention relates to an improvement 10 in roller side bearings for railway cars.

In the accompanying drawings forming a part of this specification, Figure 1 is a front elevation of a truck and body bolster of a railway car having roller side bearings embodying my invention. Fig. 2 is a top or plan view of the truck bolster showing the roller side bearings. Fig. 3 is a section on the line 3—3 of Fig. 2 on a somewhat larger scale. Fig. 4,—also upon a larger scale,—20 is a vertical section on the line 4—4 of said Fig. 2.

In said drawing 11 represents the truck bolster and 12 its opposing body bolster, the former secured to the truck and the latter to the car. Upon the body bolster are the plane bearing plates 13, 13. Secured to the truck bolster are the bearing plates 14. Between these two sets of plates 13 and 14 ride the rollers 15. Built up around each bearing plate 14 is a guard box 16, the sides of which are high enough so that the roller cannot escape when between the two bolsters. To automatically center each roller it is furnished with a radially arranged spring axle 35 17 held at the inner end 18 by a projection 19 from the guard box 16, and at its other end is inserted in an axial opening 20 in the roller 15. This axial opening is enlarged or flared at 21 on the inner face of the roller to 40 accommodate the movement; and for the same reason the holder 19 is flared at 22 at its outer end. The cavity 23 in the holder 19 passes entirely through said holder and the spring 17 may be inserted through the 45 end of the holder and secured in place by the cotter pin 24.

I prefer that the spring 17 shall be a coiled spring, such as is shown in the drawing since this form adapts itself most readily 50 to application in this connection.

In operation the roller bearings are brought into play upon the swiveling of the truck, and consequently one or other of the rollers is always free to adjust itself to a 55 central position while the weight is upon the

other roller. This adjustment to the central position is performed by the tendency of the spring to return to a straight line when released from flexure. This self adjusting roller is not only effective and durable, but 60 it is also simple and cheap in construction.

Although the radius of the flexible or spring arm is shorter than the radius of the arc of rotation of the roll, the latter, by reason of the flexibility of the arm on which it 65 is carried, will always adjust itself so that its axis will be at all times radial to the greater arc, that is to say, if the tendency of the greater arc is to cause the roll to fall back, the flexible arm will permit it to so 70 fall back, and if the tendency be to cause it to advance, the flexible arm will permit that and finally upon occasion also return the roll to the central position. It will be understood that because of this facility of adjustment of the movement of the roll to fit its 75 position on the greater arc, said roll may be made either cylindrical or in the form of the frustum of a cone inclosed between two radii of the greater arc, but owing to the 80 wedging action and the consequent end thrust of the conical form the cylindrical roll is generally to be preferred.

Having described the invention, claim is 85 made as follows:

1. A side bearing for cars including, in combination: a roller; a retaining member for the roller; and a spring attached to said member and on which the roller is mounted, said spring forming a flexible axle for the 90 roller thereby adapting the roller to rotate and move bodily, the spring acting to return it to normal position, substantially as specified.

2. The combination with a truck and a body bolster, each having a bearing plate thereon, of an interposed roller, and a radially arranged spring axle, said spring axle consisting of a coiled spring, and said roller being mounted on said spring axle, substantially as specified.

3. The combination with a truck and a body bolster, of a box-shaped bearing on said bolster, a spring axle, and a roller, said roller being mounted on said axle, and the box-shaped bearing having a radial projection for containing said spring axle, substantially as specified.

4. The combination with a truck and a body bolster, of a box-shaped bearing on said 110

bolster, a spring axle, and a roller mounted on said axle, said box-shaped bearing having a radial projection provided with a cavity therein, said cavity being adapted to contain a portion of the spring axle, and said roller having a flared cavity therein for receiving one end of the spring axle, substantially as specified.

5. The combination with a truck and a body bolster, of a box-shaped bearing on said

bolster, a spring axle, and a roller mounted on said axle, said box-shaped bearing having a cavity passing entirely therethrough, whereby the spring axle may be readily inserted, substantially as specified.

JOHN F. O'CONNOR.
